INDOOR TELEVISION ANTENNA MOUNTING

Frank E. Dudley, Philadelphia, Pa.

Application January 17, 1949, Serial No. 71,284

2 Claims. (Cl. 250—33)

1

The present invention relates to indoor television antennae and mountings therefor.

A purpose of the invention is to simplify the manipulation of a television antenna in a temporary indoor installation.

A further purpose is to avoid the twisting and confusion of electrical connections which occur when an indoor television antenna is shifted about a vertical axis to orient it directionally.

A further purpose is to provide a convenient depending support for an indoor television antenna in an electrical socket which is downwardly directed from the ceiling.

A further purpose is to provide slip rings for conducting the current between a rotating element and a fixed element of a television antenna mounting.

A further purpose is to permit angular adjustment as well as rotation of a television antenna, and preferably also of a reflector, preferably by a rotating bearing and a universal joint mounting therefrom.

Further purposes appear in the specification and in the claims.

In the drawings I have chosen to illustrate two only of the numerous embodiments in which my invention may appear, choosing the forms shown from the standpoints of convenience in illustration, satisfactory operation and clear demonstration of the principles involved.

Figure 1 is a diagrammatic central vertical section of a television antenna embodying the principles of my invention.

Figure 2 is a fragmentary perspective of a variation in the mounting of Figure 1.

Figure 3 is a fragmentary elevation showing a variation.

Describing in illustration but not in limitation and referring to the drawings:

Many persons are using indoor television antennae under circumstances in which a highly permanent mounting affixed to the wall or ceiling is undesirable. Typical examples are hotels, apartments and rented houses, where the mounting of brackets on the wall or ceiling is generally not recommended. Even with permanent bracket mountings, considerable difficulty is encountered in manipulation of an indoor television antenna, as the connections are likely to become twisted or broken.

The present invention is designed to produce an indoor television antenna which can be adjusted directionally without difficulty, and which can be mounted in an overhead electric light socket or similar fitting without the necessity of

2

making any attachment to the wall or ceiling, or with minor attachment. The device is readily moved from room to room and will be recommended in many cases even where a more permanent installation would be possible.

In the form of Figure 1, an insulating support 20, suitably of phenolic plastic or electrical porcelain, has an electric socket plug 21 at its upper end. The plug 21 carries no electrical contacts, but merely provides a support depending from an electric socket located in the ceiling and suitably downwardly directed. The standard electric plug screw thread is formed on the support. Below the screw plug portion 21, the insulation is desirably flanged at 22, and then downwardly extended at 23 in a tubular body, shouldered at 24 and reduced in diameter at the lower end 25. Intermediate the length of the body 23 is an annular flange 26 which engages a disc-like guard 27, suitably of plastic, which covers and protects the fixed contacts to be described. Below the guard 27 is a flanged insulating collar 28, suitably of phenolic plastic, which has an outwardly extending flange 30 engaging below the guard and is shouldered at 31 to engage and support a metallic slip ring 32 (suitably of copper, or brass) extending out from the plug, and having a terminal finger 33 located at one point on the circumference, extending through a slot 34 in the insulating collar 28 and into a groove 35 in the outer circumference of the plug body 23. The terminal finger 33 is contacted by a metallic bolt 36 with an electrically conducting terminal 37 in a slot 38 on the upper side of the shield 27. A terminal screw 40 connects a wire 41 from the television set to the terminal 37.

Telescoping around the insulating collar 28 below the slip ring 32 is an insulating sleeve 42, suitably of phenolic plastic, which tends to hold the slip ring 32 from below. A second slip ring 43 similar to the first surrounds the plug support below the end of the insulating collar 28 and the insulating sleeve 42. The slip ring 43 has a terminal finger 44 extending inwardly below the shoulder 24 and electrically connected by a metallic bolt 45 to the opposite side of the shield 27, where a terminal 46 in a slot 47 threads on the bolt. A terminal screw 48 connects a wire 50 from the television set to the terminal 46.

Thus it will be seen that electrical connection from the wires 41 and 50 is made to the respective slip rings, which are themselves stationarily mounted below the shield 27.

Surrounding the reduced lower portion 25 of the plug support is an annular insulating spacer

51, and below the spacer a housing 52 surrounds the plug support portion 25. The housing may suitably be a metallic casting having a bearing engaging portion 53 at the top, an annular body 54 below, opposite projecting tubular arms 55 at diametrically spaced points, and a handle supporting spider 56 at the bottom. The bearing engaging portion 53 engages the spacer 51 above and below rests on and engages the upper rotating race 57 of a ball bearing 58 having a lower cooperating race 60. The lower race 60 is supported and held from below by a washer 61 preferably of insulating material and engaged by a cap bolt 62 extending axially into the plug support, the nut portion being received in a slot 63 thereof. Thus it will be evident that the rotating parts consist of the housing 52, the parts supported thereon, and the race 57 and balls of the bearing.

The spider 56 at the bottom of the housing supports and suitably makes bolted connection with a handle 64, preferably of wheel-like character, mounted at the bottom of the housing and accessible to the user for turning the antenna.

The antenna may be of any suitable character, but in the form of Figure 1 is shown as a rod or tube 65 having a span 66 extending from end to end, and reversely bent end portions 67 at each end terminating in shorter return bent spans 68. The antenna is suitably mounted in and insulated from the housing by insulating plugs 70, preferably of phenolic plastic, suitably provided with openings 71 through which the antenna spans pass, and having plug portions 72 extending into the tubular interiors of the arms 55 of the housing. The interior of the housing is hollow and therefore the antenna is properly electrically insulated from the housing throughout. Connections are made to the opposite ends of the antenna by electric contact screws 73 in the plugs beyond the arms of the housing which connect by terminals and wires 74 to brush terminals 75 insulated from and held by insulating bushings 76 on screws 77 mounted in the upper portion of the housing at diametrically opposite points. Brushes 78 from each of the brush terminals engage one of the slip rings and maintain contact therewith as the antenna is rotated.

The form of Figure 1 may be modified if desired to permit rocking as well as rotation of the antenna, and to provide for the use of a reflector. This is shown in Figure 2 where the plug support and slip ring construction is the same as that in Figure 1. The electrical socket 80 has been there illustrated with the plug screwed into the same. The arms 55 of the housing have been extended out farther than in the form of Figure 1, and carry at their ends universal joint balls 81. The antenna 65 is here mounted by the insulating plugs 70 on a tube 82 surrounding but spaced from the antenna and carrying at one side a universal joint ball 83. The balls 81 and 83 are locked between resilient socket members 84 fastened by a screw 85 at the center and having at opposite ends socket halves 86 which engage on either side of the balls. The universal joint is thus subject to rocking either on a horizontal axis, a vertical axis or a diagonal axis to achieve angularity in adjustment of the television antenna in addition to the rotation of the housing on the main axis. At the opposite side of the housing, an identical universal joint is provided, with insulating plugs 70 extending through the tube 82 and having only a

single center opening for carrying a wire or tubular reflector antenna 87 which is locked to the plugs by set screws 73'. Since it is not necessary to connect the reflector antenna to the receiver, the set screws 73' in this case do not need to function as electrical terminal screws.

In operation it will be evident that the device can be installed very simply by unscrewing the lamp and removing the shade from an electric light socket downwardly directed in the ceiling and screwing in the antenna mounting device of the invention. The stationary wiring connections 41 and 50 are then made to the television set, after which the device is ready to operate.

15 In operation of the form of Figure 1 it is simply necessary to turn the handle 64 rotating the antenna until maximum efficiency of reception is obtained. With the form of Figure 2 the antenna and reflector antenna are rotated together, and once the preferred main orientation is established, minor adjustments in the antenna can be made both about the vertical axis and the horizontal axis and also about any diagonal axis by grasping the tube 82 and rocking or swinging the antenna in the desired direction freedom being obtained in the universal joint. Similarly 25 the reflector antenna may be adjusted to agree therewith or to vary in any desired degree from the setting of the antenna. In case it is necessary to move the device from one room to another, this can be done very simply by disconnecting the fixed electrical connections 41 and 50, and then unscrewing the plug from the electrical socket.

35 It will be understood that in view of the fact that the connections are diagrammatic, no attempt has been made to conceal the leads, brushes or slip rings in the outer contour of the device, or to style the device so that such operating mechanism will blend in with the overall appearance. It will be understood that such changes can be made without departing from the principles of the invention.

45 In some cases it may be desirable to use a special socket fitting on the ceiling rather than an electric lamp socket to support the antenna, as shown in Figure 3. In this form a socket 88 desirably having the electric lamp thread, is mounted on the ceiling 90 by screws 91 thus holding 50 the plug of the antenna in the same manner as a lamp socket.

55 In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

60 Having thus described my invention what I claim as new and desire to secure by Letters Patent is:

1. In a television antenna, a screw plug 65 adapted to engage a socket, slip rings on and depending from the plug, terminals on the plug connected to the slip rings, a bearing on the plug, a housing rotatably in the bearing, brushes on the housing engaging the respective slip rings, a universal joint connected to the housing, and 70 a television antenna mounted on the universal joint and electrically connected to the brushes.

2. In a television antenna, a screw plug 75 adapted to engage a socket, slip rings on and depending from the plug, terminals on the plug connected to the slip rings, a bearing on the plug,

a housing rotatable in the bearing, brushes on the housing engaging the respective slip rings, a universal joint connected to the housing on one side thereof, a television antenna mounted on the universal joint and electrically connected to the brushes, a second universal joint on the housing at the opposite side thereof and a reflector antenna mounted on the opposite universal joint.

FRANK E. DUDLEY.
